UNITED STATES PATENT OFFICE

2,599,009

HONE

John J. Palotsee, Youngstown, Ohio

Original application December 6, 1946, Serial No. 714,459. Divided and this application September 16, 1949, Serial No. 116,085

4 Claims. (Cl. 51—184.3)

1

This invention is a novel adjustable hone, particularly adapted for use in hone rotating machines, preferably but not necessarily of the type shown in my U. S. Letters Patent No. 2,358,247, dated September 12, 1944, the present invention being an improvement upon the hones disclosed in my U. S. Letters Patent No. 1,269,378, dated January 6, 1942; No. 2,332,463, dated October 19, 1943; and No. 2,338,963, dated January 11, 1944; also, the hone shown in my co-pending application Serial No. 585,629, filed March 30, 1945 (now Patent No. 2,412,419, dated December 10, 1946).

The present application is a division of my co-pending application Serial No. 714,459, filed December 6, 1946, issued as Patent No. 2,543,193, dated February 27, 1951.

The principal object of the present invention is to provide an adjustable abrasive cylindrical hone, particularly adapted for grinding, machine finishing, polishing, cylindrical bearings or the like, the hone consisting of a spindle carrying an annular series of radially disposed blades each carrying Carborundum or other abrasive hone sections or carrying tubular flexible abrasive cylinders, the blades when fully contracted around the spindle forming a substantially cylindrical surface, the blades and spindle being provided with complementary tapered surfaces cooperating with means for shifting the assembly of blades axially of the spindle to effect expansion or contraction of the hone with respect to the spindle.

Other minor objects of the invention will be hereinafter set forth.

I will explain the invention with reference to the accompanying drawings which illustrate several practical embodiments thereof, to enable others familiar with the art to adopt and use the same; and will summarize in the claims, the novel features of construction, and novel combinations of parts, for which protection is desired.

In said drawings:

Figure 1 is a side elevation, partly in section, showing one form of hone embodying my invention.

Fig. 2 is an enlarged transverse section on the line 2—2, Fig. 1.

Fig. 3 is a top plan view of the spindle, detached.

Fig. 4 is an enlarged transverse section on the line 4—4, Fig. 3.

Fig. 5 is a side elevation of one form of the blades, detached.

Fig. 6 is an end view of the blade shown in Fig. 5.

Fig. 7 is a top plan view of the preferred form of blade, detached.

2

Fig. 8 is a transverse section on the line 8—8, Fig. 7.

Fig. 9 is a plan view, partly in section, showing an abrasive flexible cylinder adapted to be mounted upon the hone.

Fig. 10 is an end view of a modified cylinder shown in Fig. 9.

Fig. 11 is an elevation of a grooved modified blade for carrying a stone hone section cemented thereon.

Fig. 12 is a plan view of the stone section used with the blade shown in Fig. 11.

Fig. 13 is a transverse section of the spindle, blades, and stones shown in Figs. 11 and 12.

Fig. 14 is a plan view of the blades of another modified hone adapted to use an abrasive coated sleeve.

Fig. 15 is a plan view of the abrasive coated sleeve used on the hone shown in Fig. 14.

Fig. 16 is a transverse section through the spindle blades and sleeve shown in Figs. 14 and 15.

The hone shown in Figs. 1-10 inclusive comprises a spindle 1, shown more particularly in Figs. 3 and 4, said spindle being of small cylindrical shape, and being threaded as at 1a at one end, whereby the same may be mounted in a socket H' of the flexible shaft H of a honing machine such as shown in my U. S. Letters Patent No. 2,358,248 aforesaid; however, the spindle 1 may be mounted for rotation on any other desired machine. The opposite end of spindle 1 is threaded as at 1b. Intermediate the threaded portions 1a, 1b is an annular series of spaced grooves 1c, having inclined bottoms, three such series being shown in Fig. 4, evenly spaced apart around the circumference of the spindle. The bottoms of grooves 1c all slope in the same direction and have the same angularity with respect to the axis of spindle 1, and the lower or deeper ends thereof are preferably rounded upwardly as at 1d (Fig. 1).

On spindle 1 adjacent the threaded portion 1a is a collar 2 having a conical recess 2a in its inner end, and having an annular recess 2b at its outer end. Threaded upon the portion 1a beyond the collar 2 is a nut or collar 3 having a non-circular outer end 3a to facilitate turning, the main portion of the outer surface of the nut being knurled as at 3b to assist manual turning of the nut. At the inner end of nut 3 is an annular flange 3c receiving the recessed end 2b of collar 2, and preferably the annular flange 3c is provided with calibrations 3d cooperating with a zero mark on the collar 2 to assist the operator in determining variations in diameter of the hone.

Adjacent the opposite end of spindle 1 is a collar 4 similar to collar 2, same having a conical recess 4a in its inner end. A nut 5 is provided on the threaded portion 1b of spindle 1 and is locked in position by set screw 6. Around spindle 1 between the nut 5 and the collar 4 is a spring 7, normally urging collar 4 towards the collar 2, for the purpose hereinafter described.

Around spindle 1 between the collars 2 and 4 is an annular series of blades 8, three being shown in Fig. 2. As shown more particularly in Figs. 2, 5, 6 and 7, the blades 8 are arcuate in cross section, the inner surfaces conforming in curvature to that of the spindle 1, as shown in Fig. 2. On the under side of each blade 8 at the center thereof are spaced aligned inclined ribs 8a having their inner lower edges shaped to conform with the shape of the inclined grooves 1c in spindle 1, the ribs 8a conforming in spacing and width to the grooves 1c, as shown in Fig. 1. The ends of blades 8 are oppositely beveled as at 8b to conform with the conical recesses 2a and 4a of the collars 2 and 4, the conical recesses engaging the inclined ends 8b whereby the annular series will be yieldably positioned around the spindle by action of the spring 7.

The outer side edges of each of the blades 8 may be recessed as at 8c, although the recesses may, if desired, be omitted. As shown in Fig. 7, the outer surface of each blade 8 preferably has a series of shallow holes 8d in which suction is set up to assist in retaining the cylindrical flexible abrasive sleeve 9 on the assembly of blades when placed thereon, the abrasive sleeve 9 being of length conforming with that of the blades 8. The holes 8d will serve, by suction, to maintain the abrasive cylinder 9 on the blades to prevent slippage or shifting during the honing operation. By the above construction, when the nut 3 is rotated relative to the spindle 1, the collar 2 will be shifted towards the collar 4, which will yield under pressure of spring 7 and the series of blades 8 will be shifted axially of spindle 1, causing the inclined ribs 8a to ride upwardly in their inclined slots 1c in the spindle whereby the diameter of the hone will be enlarged.

The abrasive coated sleeves 9 may be made of any suitable material whose surface is coated with abrasive. Ribs 9x (Fig. 10) may be provided in the bores of the sleeves 9 to engage the grooves 8c in the blades (Fig. 2) to prevent the sleeve from turning on the hone during operation thereof. The use of the flexible abrasive sleeves 9 as a cutting tool makes it possible to use a relatively long spindle and blades since the blades 8 themselves may be made thicker than those which carry stone hone sections, and the thicker blades are obviously more rigid throughout their length. The use of the sleeves 9 also provides for greater accuracy since wear thereon is relatively even and the diameter of the hone will remain substantially uniform. A worn sleeve 9 may be quickly and easily replaced by a new one, thus making my hone economical to use. The sleeves 9 are readily available in various diameters for use on the same hone when adjusted to corresponding diameters, and thus the hone is not limited to use with sleeves of only one diameter.

In Figs. 11, 12 and 13 a modification is shown in which the blades 10 as in the preceding figures have beveled ends and have the inclined ribs on their under sides. In this modification, however, the outer face of each blade 10 is provided with a shallow V-shaped helical groove 10a through-

out its length, the pitch being relatively small as indicated in Fig. 11, and the groove 10a preparing the surface of the blades 10 for the cement which secures an arcuate-shaped stone hone 11 thereto, the assembly of stones 11 when the blades 10 are fully contracted around the spindle 1 forming a substantially cylindrical surface, as shown in Fig. 13.

In Figs. 14, 15 and 16 a further modification is shown in which the blades 12 are generally similar to those in the preceding modifications with the exception that their outer surfaces are provided with oppositely extending helical shallow V-shaped grooves 12a and 12b respectively, as shown in Fig. 14, adapted to prevent turning of the abrasive coated sleeve 13 mounted around the blades 12, the grooves 12a and 12b replacing the holes 8d in the blade shown in Fig. 7 but serving the same purpose.

I do not limit my invention to the exact form shown in the drawings, for obviously changes may be made therein within the scope of the claims.

I claim:

1. An adjustable hone, comprising a spindle of substantially uniform cross-sectional size and shape throughout its length and having an annular series of spaced aligned grooves therein having their bottoms inclined in the same direction and disposed at the same angle to the axis of the spindle; and annular series of blades around the spindle having their inner faces conforming with the shape of the spindle, each blade having a series of axially disposed aligned ribs on its inner face engaging the sides and bottoms of their related grooves, said ribs having their inner faces inclined in the same direction as and at the same angle as the bottoms of the grooves; said series of blades when in fully retracted position forming a substantially cylindrical surface, means yieldably maintaining the blades positioned around the spindle while permitting the blades to be simultaneously shifted axially of the spindle to vary the diameter of the hone; and abrasive member carried by the blades; said blades having helical grooves in their outer faces of relatively small pitch; and said abrasive member comprising stone hone sections adhesively secured to their respective blades and together forming a cylindrical abrasive surface when the blades are fully retracted.

2. An adjustable hone comprising a cylindrical spindle of substantially uniform size and having an annular series of spaced aligned grooves therein having their bottoms inclined in the same direction and disposed at the same angle to the axis of the spindle; an annular series of blades around the spindle having their inner and outer faces conforming with the curvature of the spindle, each blade having a series of axially disposed aligned ribs on its under side engaging the sides and bottoms of their related grooves, said ribs having their inner faces inclined in the same direction as and at the same angle as the bottoms of the grooves; means yieldably maintaining the blades positioned around the spindle while permitting the blades to be simultaneously shifted axially of the spindle to vary the diameter of the hone; an abrasive member carried by the blades; said blades having helical grooves in their outer faces of relatively small pitch; and said abrasive member comprising stone hone sections adhesively secured to their respective blades and together forming a cylindrical abrasive surface when the blades are fully retracted.

3. An adjustable hone, comprising a spindle of substantially uniform cross-sectional size and shape throughout its length and having an annular series of spaced aligned grooves therein having their bottoms inclined in the same direction and disposed at the same angle to the axis of the spindle; an annular series of blades around the spindle having their inner faces conforming with the shape of the spindle, each blade having a series of axially disposed aligned ribs on its inner face engaging the sides and bottoms of their related grooves, said ribs having their inner faces inclined in the same direction as and at the same angle as the bottoms of the grooves; said series of blades when in fully retracted position forming a substantially cylindrical surface, means yieldably maintaining the blades positioned around the spindle while permitting the blades to be simultaneously shifted axially of the spindle to vary the diameter of the hone; an abrasive member carried by the blades; and said abrasive member comprising stone hone sections secured to their respective blades and together forming a cylindrical abrasive surface when the blades are fully retracted.

4. An adjustable hone comprising a cylindrical spindle of substantially uniform size and having an annular series of spaced aligned grooves

therein having their bottoms inclined in the same direction and disposed at the same angle to the axis of the spindle; an annular series of blades around the spindle having their inner and outer faces conforming with the curvature of the spindle, each blade having a series of axially disposed aligned ribs on its under side engaging the sides and bottoms of their related grooves, said ribs having their inner faces inclined in the same direction as and at the same angle as the bottoms of the grooves; means yieldably maintaining the blades positioned around the spindle while permitting the blades to be simultaneously shifted axially of the spindle to vary the diameter of the hone; an abrasive member carried by the blades; and said abrasive member comprising stone hone sections secured to their respective blades and together forming a cylindrical abrasive surface when the blades are fully retracted.
